UNITED STATES PATENT OFFICE.

ERNEST C. LEWERENZ, OF UTICA, MICHIGAN.

COMBINATION COMB AND TOOTH-BRUSH HOLDER.

1,196,959.

Specification of Letters Patent.

Patented Sept. 5, 1916.

Application filed January 13, 1916. Serial No. 71,918.

To all whom it may concern:

Be it known that I, ERNEST C. LEWERENZ, a citizen of the United States, residing at Utica, in the county of Macomb and State 5 of Michigan, have invented certain new and useful Improvements in Combination Comb and Tooth-Brush Holders, of which the following is a specification.

This invention relates to an improved 10 combination comb and tooth brush holder, and the principal object of the invention is to provide the back of a comb with a chamber so constructed that a tooth brush having an improved type of handle may be securely held in the back of the comb.

Another object of the invention is to so construct the handle of the tooth brush that it will be wedged in the chamber formed in the comb back and thus held in this place 20 by frictional engagement.

This invention is illustrated in the accompanying drawings wherein—

Figure 1 is a side elevation showing the improved comb with the tooth brush in place; Fig. 2 is a longitudinal sectional view through the comb with the tooth brush shown in elevation; Fig. 3 is a sectional view taken along the line 3—3 of Fig. 2; Fig. 4 is a sectional view taken along the line 4—4 30 of Fig. 2; Fig. 5 is a fragmentary sectional view through one end of the comb back.

The back 10 of the comb 11 is provided with a longitudinally-extending chamber 12 in which the tooth brush is placed and which 35 is provided with a flared mouth 13. This flared mouth 13 is provided so that the tapered head 14 of the tooth brush handle 15 will be wedged in the mouth 13 when the tooth brush is placed in the chamber 12 thus 40 causing the tooth brush to be held in place by frictional engagement between the head 14 and the mouth 13. The handle of the tooth brush is substantially the same width as the width of the chamber 12 so that when 45 the brush is in place as shown in Figs. 3 and 4, the brush can not have transverse play in the chamber which would tend to work the brush loose. The head 14 of the brush extends beyond the comb head 10 when the 50 brush is in place, and has its outer end pro-

vided with notches 16 which permit the brush to be easily withdrawn from the comb when desired.

The comb and brush can be formed of any suitable material, such as celluloid, molded 55 rubber, or any other composition, or may be formed of metal if desired. By having the comb and brush constructed as shown, the comb may be used with the brush in place and then put in the pocket or the brush may 60 be withdrawn from the chamber 12, and after being used, can be replaced and the comb placed in the pocket. It will therefore be seen that a comb and brush have been provided which can be very conveniently carried about in the pocket so that the comb and brush will always be convenient when desiring to use the same. It will also be noted that the comb and brush are so constructed that they may be securely held in 70 the position shown in Fig. 2, but the brush may be easily withdrawn when desiring to use the same. It will also be noted that if desired, openings may be formed in the walls of the chamber so that air can circulate in 75 the chamber and thus permit the brush to dry.

What is claimed is:

A comb having its back provided with a longitudinally extending chamber of even 80 transverse diameter throughout its length, the upper and lower walls being thickened at one end to provide a restricted neck and flared mouth, a brush fitting in said chamber and having its head and handle of substantially the same width as said chamber to prevent said brush from moving transversely therein and guide the movement of the brush into the chamber, the handle of said brush being provided with an enlarged 85 and tapered end conforming to the contour of the flared mouth of said chamber whereby the enlarged end of the handle may be wedged in the mouth of the chamber.

In testimony whereof I affix my signature 90 in presence of two witnesses.

ERNEST C. LEWERENZ.

Witnesses:

EDMUND PETERS,

Mrs. E. LEWERENZ.
